UNITED STATES PATENT OFFICE.

CHARLES GEORGE EIDSON AND THOMAS DAVIS, OF BALTIMORE, AND DAVID ELDRIDGE CROUSE, OF ANNAPOLIS, MARYLAND, ASSIGNEES, BY MESNE ASSIGNMENTS, TO THE JOHN FORD STARTER COMPANY, OF BALTIMORE, MARYLAND, A CORPORATION OF MARYLAND.

ROTARY MOTOR.

1,320,679.

Specification of Letters Patent.

Patented Nov. 4, 1919.

Application filed January 14, 1916, Serial No. 72,069. Renewed August 23, 1919. Serial No. 319,517.

To all whom it may concern:

Be it known that we, CHARLES G. EIDSON and THOMAS DAVIS, residents of Baltimore city, in the State of Maryland, and DAVID E. CROUSE, a resident of Annapolis, in the county of Anne Arundel, in the State of Maryland, all citizens of the United States, have made certain new and useful Improvements in Rotary Motors, of which the following is a specification.

Our invention relates to improvements in rotary motors, and it consists in the combinations, constructions, and arrangements herein described and claimed.

An object of our invention is to provide an arrangement by means of which an internal combustion engine such as the motor of an automobile, may be started by the pushing of a pedal or other similar device, said starting being accomplished by the use of compressed air.

An object of our invention is to provide a motor designed to be run by air pressure, said motor being of the so-called rotary type in which sliding pistons and stationary abutments are made use of.

A further object of our invention is to provide a motor having means for equalizing the pressure on the ends of spring pressed sliding pistons, thereby insuring the contact of the pistons with the walls of the casing.

A further object of our invention is to provide means for producing the impact of the slideable pistons against the stationary abutments.

Other objects and advantages will appear in the following specification, and the novel features of the invention will be particularly pointed out in the appended claims.

Our invention is illustrated in the accompanying drawings forming a part of this specification, in which:

Figure 1 is a section through the motor, compressor and a portion of the clutch operating mechanism.

Fig. 2 is a section along the line 2—2 of Fig. 1, looking in the direction of the arrows.

Fig. 3 is a perspective view of one of the rotor blades or pistons.

Fig. 4 is a perspective view of one of the stator blades or abutments.

Referring now particularly to Figs. 1 and 2, we have shown therein a shaft 1.

One end of this shaft bears a clutch member 2 such as that ordinarily used in starting a motor or engine by hand with a crank. The shaft revolves in the interior of a sleeve 3 which is provided with anti-friction linings 4. The sleeve 3 is disposed in the interior of a hub 5 and is provided with a key 6 which slides in a groove 7 in the hub 5 so that the sleeve may have a longitudinal movement with respect to the hub, and any rotary movement of the hub will be transmitted to the sleeve. The hub 5 is provided with radially extending walls 8 which terminate in an integral cylindrical member 9. At 10, see Fig. 2, we have shown radially disposed members similar to the spokes of a wheel. These members 10 extend from one wall 8 to the other and are slotted or cored as shown at 11 to receive blades or pistons 12 which are adapted to slide radially with respect to the axis of the shaft 1. The blades or pistons are like that shown in Fig. 3. Each piston is provided with a recess 12^a and with bores 12^b extending from one edge of the piston nearly to the other edge. Laterally extending holes 12^c communicate with the bores as shown in Fig. 3.

At the inner end of the slots or cored out places 11 we provide lugs which extend from one wall of the slot to the other, these lugs being for the purpose of strengthening the spokelike members 10 and being secured to the hub 5 by means of screws 14. It is obvious that the lugs might be formed integrally with the members 10 but we prefer to make them in the manner described because of ease in construction. The lugs 13 are arranged to enter the slots 12^a when the pistons are moved inwardly. Springs 15 are provided and are disposed within the bores 12^b, these springs tending to force the pistons outwardly.

The parts 5 to 15 inclusive constitute what we term the rotor and its pistons. The stator comprises an outer casing composed of the radially extending side walls 16 and an outer cylindrical concentric portion 18 spaced from the member 9 as clearly shown in the drawings. The walls 16 have lateral extensions 16^x which form bearings for the sleeve 5. At opposite portions of the cylindrical member 17 are offsets 19 into which springs 20 may play. These springs 20 are disposed adjacent to approaches 21 which

also serve as means for retaining the sliding abutments 22. These approaches are preferably formed as an integral casting with the wall of the cylinder 17 but may be made 5 separately and secured to the wall. The sliding abutments are best shown in Fig. 4. From this figure it will be observed that each of the abutments is provided with bores 22^a, that the edge of the abutment is 10 cove as shown at 22^x to hug the cylinder 9, and that each abutment is provided with a groove 22^b which is arranged to register with a passage 23 leading to the space between the cylinders 9 and 17.

15 On the opposite side of the abutment, see Fig. 2, the member 21 is sloped toward the cylinder 17. A spring 24 is disposed in the offset into which the intake pipe 25 is secured. On the opposite side of the 20 shaft a similar arrangement is provided.

Referring now particularly to Fig. 1, it will be seen that the shaft 1 passes through the casing 26 of the air compressor. This casing is provided with an extension 26^a 25 which forms a bearing for the clutch 2, a lining 26^b being provided. At the end of the extension 26^a is a hinged cap 27 which is provided with a spring clasp 28 that normally holds the cap closed over the end of the extension.

Secured to the shaft 1 is an eccentric member 29 which, as will be noted, is provided with a strap 30. The eccentric 29 is wider than the strap in order that it may 35 have a longitudinal movement with the shaft as explained later. The strap of the eccentric is connected to a piston 31 disposed in the cylinder 32. The latter constitutes the cylinder of the compressor and is provided 40 with check valves 33 and 34.

Referring now particularly to Fig. 2, the air is shown entering from the pipes 25 into the space between the cylinders 9 and 17, the pistons 12 being extended to engage the 45 walls of the cylinder 17. The rotor will therefore be turned since the compressed air is acting on opposite sides of the pistons which are situated on the opposite sides of the shaft 1. It will also be observed that the other bore of piston 12 is in a position to provide for the exhaust of the air through the exhaust ports 71. The exhaust does not take place directly into the atmosphere but the space 72 between the outer cylindrical 50 portion 18 and the cylindrical member 17 serves the purpose of a muffler. The exhaust finally takes place at the opening 73. This opening 73 is disposed in such position that the spent air must travel a considerable 55 distance before finally escaping. This tends to reduce the noise of the engine and to eliminate the whistling or hissing sound.

In Fig. 2 those pistons 12 which have just passed over exhaust ports 71, will engage the springs 20. This tends to lessen

the shock occasioned by striking the approaches 21. The latter are in the form of cams which cause the slideable pistons to retract against the tension of the springs 15 and thus permit the pistons to pass the abutments 22. After passing these abutments the pistons 12 are thrust forward by the springs 15 until they again contact with the inner walls of the cylindrical member 17. The springs 24 are for the purpose of cushioning 75 the engagement of the pistons 12 with the walls 17.

It will be noted that the full pressure of the steam comes on the end of the piston 12 immediately after passing the abutment. 80 This would tend to press the piston inwardly away from the wall of the casing were it not for the fact that the steam passes through the openings 12^c, see Fig. 3, and gets behind the piston, thereby equalizing the 85 pressure and permitting the springs 15 to exert their maximum tension to hold the pistons in close engagement with the wall of the casing.

It will be noted that when air enters the 90 space between the members 9 and 17, it passes at once to the inner end of the piston through the openings 12^c and the bores 12^b. Thus the air pressure is equalized so that the holding of the pistons against the walls 95 of the outer cylindrical member is assured. Similarly the air enters through the passages 23 and 22^b, gets behind the sliding abutments 22 so as to aid the springs 73 to hold the abutments in close engagement 100 with the outer surface of the inner cylinder 9. Simultaneously with the starting of the motor, the pressure of the pedal 46 causes the movement of the lever 41 through the medium of the rod 43 and lever 44, and this 105 brings the clutch members 3^x and 49 into operative engagement, thereby imparting a rotary movement to the shaft 1.

We claim:—

1. A rotary motor comprising a stator, a 110 cylindrical rotor spaced from said stator and having a series of spokes, radially movable pistons carried by said rotor, springs arranged to bear on the inner ends of said pistons for forcing them outwardly, said 115 springs being disposed in recesses in the spokes of the rotor, means for equalizing the pressure on the ends of said pistons, said means comprising passages in said pistons arranged to establish communication with 120 the space between the rotor and the stator, and the recesses containing the spring, abutment supports carried by the stator, and having cam surfaces arranged to be engaged by the pistons of said rotor to move the 125 pistons inwardly against the tension of the springs, and springs carried by said stator at each end of said abutment supports for cushioning the impact of the slideable pistons during the movement of the pistons to 130

ward and away from said abutment supports.

2. A rotary motor comprising a stator, a cylindrical rotor spaced from said stator, 5 radially movable pistons carried by said rotor, springs arranged to bear on the inner ends of said pistons for forcing them outwardly, abutment supports carried by said stator and having cam surfaces arranged to 10 be engaged by the pistons of said rotor to move the pistons inwardly against the tension of the springs, and springs carried by said stator at each end of said abutment supports for cushioning the impact of the 15 slid- able pistons during the movement of the pistons toward and away from said abut- ment supports.

3. A rotary motor comprising a stator, a cylindrical rotor spaced from said stator, 20 radially movable pistons carried by said rotor, springs arranged to bear on the inner ends of said pistons for forcing them outwardly, abutment supports carried by said stator and having cam surfaces arranged to 25 be engaged by the pistons of said rotor to move the pistons inwardly against the tension of the springs, springs carried by said stator at each end of said abutment supports for cushioning the impact of the 30 slid- able pistons during the movement of the pistons toward and away from said abut- ment supports, a slid- able abutment carried by each of said abutment supports, and 35 springs for forcing said slid- able abutments into contact with the surface of the rotor.

4. A rotary motor comprising a stator, a cylindrical rotor spaced from said stator, 40 radially movable pistons carried by said rotor, springs arranged to bear on the inner ends of said pistons for forcing them outwardly, abutment supports carried by said stator and having cam surfaces arranged to 45

be engaged by the pistons of said rotor to move the pistons inwardly against the tension of the springs, springs carried by said 50 stator at each end of said abutment supports for cushioning the impact of the slid- able pistons during the movement of the pistons toward and away from said abutment supports, a slid- able abutment carried by each of 55 said abutment supports, springs for forcing said slid- able abutments into contact with the surface of the rotor, and means for admitting fluid pressure to the outer end of said slid- able abutments for assisting the springs.

5. A rotary motor comprising a stator, a cylindrical rotor spaced from said stator, 60 radially movable pistons carried by said rotor, springs arranged to bear on the inner ends of said pistons for forcing them outwardly, abutment supports carried by said stator and having cam surfaces arranged to 65 be engaged by the pistons of said rotor to move the pistons inwardly against the tension of the springs, springs carried by said stator at each end of said abutment supports for cushioning the impact of the slid- able pistons during the movement of the pistons 70 toward and away from said abutment supports, a slid- able abutment carried by each of said abutment supports, springs for forcing said slid- able abutments into contact with the 75 surface of the rotor, and a passage in each of said abutment supports communicating at one end with the fluid pressure intake and at the other end with the rear of the abutments for permitting the fluid pressure to assist the springs.
